SAFETY SWITCH AND RESETTING
MECHANISM THEREFOR

Gordon H. Brown, Detroit, Mich.

Application February 16, 1945, Serial No. 578,137

11 Claims. (Cl. 200—138)

1

This invention relates to a safety switch and resetting mechanism therefor.

Principal objects of the invention are to provide:

A new and improved safety switch and resetting mechanism for electric teakettles and appliances of a similar nature;

A thermostatic safety switch which can be reset by pushing the current conducting plug attached to the current connectors on a heated device thereagainst;

A thermostatic safety switch having simple and easily operable means for resetting such switch.

Other and further objects of the invention will be apparent from the following description and claims and will be understood by reference to the accompanying drawings, of which there are two sheets, which, by way of illustration, show preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims. I also contemplate that of the several different features of my invention, certain ones thereof may be advantageously employed in some applications separate and apart from the remainder of the features.

In the drawings:

Fig. 1 is a side elevational view of an electric teakettle embodying the invention, certain of the parts thereof being broken away.

Fig. 2 is a plan view of the teakettle;

Fig. 3 is an enlarged sectional view of one form of the thermostatic safety switch and resetting mechanism;

Fig. 4 is a horizontal sectional view taken along the staggered line 4—4 of Fig. 3;

Fig. 5 is a fragmentary front elevational view with certain parts of the handle and shell broken away;

Fig. 6 is a fragmentary rear elevational view;

Fig. 7 is an enlarged vertical sectional view through the thermostatic safety switch and resetting mechanism but with some of the parts shown in elevation;

Fig. 8 is a schematic view illustrating the wiring diagram;

Fig. 9 is a view similar to Fig. 3 but illustrating a modified form of the invention; and

2

Fig. 10 is a perspective view of certain of the parts of the manually operable resetting mechanism for the thermostatic safety switch illustrated in Fig. 9.

5 An electric teakettle embodying the invention may comprise a shell 10 having a heating element 12 therein, a cover 14, a handle 16, and thermostatic safety switch and resetting mechanism which is partially illustrated in Figs. 3 and 4.

The shell 10 may be formed to provide a vessel which may be of generally oval shape for holding water, and a pouring and filling spout 20. The cover 14 preferably is secured removably to the rim of the shell.

10 The cover 14 may be formed of a die casting of aluminum or other suitable material and is assembled on the shell in such a manner as to close the top of the same except for the opening 20 provided by the spout 20.

The handle 16, which may be formed of plastic or other suitable material, at its front is secured to the cover by a bolt 38 and at its rear by two bolts 40. As the heads of the bolts 38 and 40 are on the under side of the cover 14, the handle 16 must be assembled to the cover 14 before the same is assembled to the shell 10. In addition, all of the apparatus or mechanism is assembled to the cover 14, and such assembly must take place before the cover 14 is secured to the shell 10. The rear of the handle is enlarged to form a cavity which cooperates with a suitable depression or recess formed in the cover 14 at the rear thereof to provide an enclosure or housing for the thermostatic safety switch and resetting mechanism.

15 The cover 14 below the aforementioned cavity at the back thereof is formed to provide a depending part 44 upon which the heating element 12 is mounted. Such part 44 includes a pair of sockets 46 in which the ends of the heating element 12 are secured. The heating element may comprise an electric resistance heating element of the type in which an electric resistance is embedded in a refractory insulation encased in a tube or sheath. The heating element 12 is arranged in the form of a loop which is arranged adjacent the bottom of the shell 10. The upper ends of the sockets 46 are threaded to receive 20 nuts 48 which cooperate with packing in the sockets 46 and the ends of the element 12 for securing the same in place. Between the sockets 46 a well 50 is formed in the depending part 44.

25 The bimetallic element 52 of a thermostatic safety switch has its lower end embedded in a

mass of metal 54 disposed in the bottom of well 50. An insulating block or panel 56 is mounted at the front of the recess and on the cover 14 by bolts 58, and this insulating block 56 has mounted thereon spring mounted contacts 60 and 62, each of the contacts being carried by a strip which is bolted by a bolt and nut assembly 64 to the block 56. The upper end of the bimetallic element 52 is in the form of a cross and includes laterally extending arms 66. A lever assembly 68 is mounted on the upper knife edge of the part 70 of the bimetallic element 52 which projects above the arms 66. The lever assembly 68 includes a U-shaped lower end, the legs 72 and 74 of which straddle the part 70 as illustrated in Fig. 3.

A lining (not shown) may be arranged inside the U-shaped lower end of the lever assembly 68 so that the latter is free to rock or slide upon the knife edge which is provided on the top of the upper end 70 of the bimetallic element, and suitable means may be employed to keep the lever assembly 68 in place on the upper edge of element 52.

The upper end of the lever assembly has universally mounted thereon a bridge 76 which bridges the contacts 60 and 62 when the parts are arranged as illustrated in Figs. 3 and 4. In this position the circuit through the heating element 12 is closed.

The bimetallic element 52 and lever 68 comprise a toggle mechanism for automatically opening the switch (comprising the contacts 60, 62 and the bridge 76) when the temperature of the heating element becomes excessively high, which usually happens when the teakettle is operated for too long a time without an adequate amount of water in the shell 10, the heat being conducted through the outer wall of the element 12 to the part 44 and thence through the metal 54 to the bimetallic element 52. During normal operation the bimetallic element 52 and lever 68 are in the position illustrated. However, when the temperature of the heating element 12 becomes too high, as previously described, the upper end 70 of the bimetallic element 52 will move to the left (Fig. 3) sufficiently to throw the upper end of the lever 68 to the right sufficiently to move the bridge 76 so as to open the switch.

The lever 68 includes laterally extending arms 80. Springs 82 connected to the arms 80 of the lever 68 and the arms 66 of the bimetallic element 52 bias the bridge 76 either towards or away from the contacts 60 and 62. As the bimetallic element 52 heats up, the upper end 70 thereof moves gradually to the left (Fig. 3) and as soon as the arms 80 of the lever 68 move to the right past the knife edge on the upper end 70 of the bimetallic element, the springs 82 will snap the lever to the right thereby rapidly opening the switch. For the sake of clarity, the springs 82 are omitted from Fig. 3.

In order to close the switch it is necessary to reset the same, and this is accomplished in the following manner and with the use of the following resetting mechanism. A plate 84 mounted by bolts 86 on the cover 14 is turned up at one end to provide a wall 88 which has rigidly mounted thereon two rearwardly extending pins 90. The pins 90 extend through guide holes in a plate 92. Plate 92 has securely mounted thereon a forwardly extending pin 94 which extends through a hole in the wall 88. The pins 90 are surrounded by springs 96 which bias the plate 92 to the position in which it is illustrated in Figs. 3 and 4. Shoulders 100 and 101 formed on the

handle limit the movement of the plate 92. Thus the plate 92 is mounted on the wall 88 and for reciprocating movement relative thereto by the pins 90 and 94.

The plate 92 carries prongs forming terminal connectors 102 which are adapted to fit within the terminal sockets carried by a conventional plug 104 on the end of a current conductor. The enclosure formed by the cover 14 and the handle 16 which encloses the thermostatic safety switch and resetting mechanism is open at the back so that such plug may be operatively associated with the terminals 102 which through the thermostatic safety switch are operatively connected with the heating element 12.

The pin 94 is adapted to contact the lever 68, when the thermostatic safety switch is open, for resetting the same. This resetting operation is accomplished when the plug 104 is mounted on the terminals 102 by pushing the plug forwardly or to the left, looking at Figs. 3 and 4. This causes a forward movement of the plate 92 and pin 94 which will engage the lever 68 if the switch is open and push it past the center of the toggle for closing the safety switch, provided that the heating element 12 and bimetallic element 52 have cooled down sufficiently to allow the switch to be closed.

The rear end of the plate 84 has two downwardly extending tabs 110, each of which is provided with a threaded hole with which a screw 112 is cooperable for removably securing in place the terminal shroud 114 which conceals the joint between the handle and the shell 10 at the rear of the kettle. The shroud 114 is shaped to fit the edges of the handle and the back of the shell and has an opening for the plug 104 and through which the terminals 102 project.

The leads between the various terminals have been omitted for the sake of clarity, but the circuit is indicated in Fig. 8 wherein it appears that one of the terminals 102 is connected to a terminal 130 for the contact 62. The other terminal 102 is connected to a terminal 132 of one end of the heating element 12 while the other terminal 134 of the heating element 12 is connected to the terminal for the switch contact 60.

A signal light 136 comprising the usual high resistance filament may be connected across the terminals of the switch contacts 60 and 62 and arranged so that when such contacts are open the signal will be illuminated. The signal may be mounted above the panel 56 and be visible through a window 138 arranged in the handle 16 above the light 136.

In the modified form of reset mechanism illustrated in Figs. 9 and 10, the terminals 102 are mounted on a bracket 200 which is suitably secured and fixed to the bottom wall 202 of the cavity which houses the thermostat and reset mechanism. A bracket 204, illustrated in Fig. 10, and provided with legs 206, is rockably mounted by means of the legs 206 in suitable sockets formed in the bracket 200. Springs 208 normally position the bracket 204 as illustrated in Fig. 9.

The bracket carries a rod 210, the upper end of which is provided with a push button 212 which projects through an opening in the top wall of the cavity. The lower end of the rod 210 is seated on a horizontal part 214 of the bracket 204 and located relative thereto so that downward pressure on the push button 212 will tend to rock the bracket 204 in a counterclockwise direction (Fig. 9) about its pivotal mounting and against the tension of the spring 208.

The bracket 204 carries a finger 216 which is engageable with the lever 68 when the thermostatic switch is open for shifting the lever 68 back to its position as illustrated in Fig. 9 for closing said thermostatic switch provided that the bimetallic element 70 thereof has cooled down sufficiently. The thermostatic switch mechanism otherwise is the same as that illustrated in Figs. 1 to 8. After release of the push button 212 the bracket 204 will return to the position as illustrated in Fig. 9 under the action of springs 208 since each spring is connected to brackets 200 and 204.

This application is a continuation in part of my prior copending application Serial No. 539,201, filed June 7, 1944, for "Electric Tea-kettle and Cover Assembly."

While I have illustrated and described preferred embodiments of my invention, it is understood that these are capable of modification and I therefore do not wish to be limited to the precise details set forth but desire to avail myself of such changes and alterations which fall within the purview of the following claims.

I claim:

1. Safety switch and resetting mechanism for the electric circuit of a heated device comprising a thermostatic switch in said circuit, terminal connectors for said circuit adapted to be removably coupled with a plug of a current conductor, said switch comprising a plurality of contacts, at least one of which is movable, a thermally responsive element operable by heat from said device for moving said contact to open said circuit, and means engageable with said movable contact and operable by pushing said plug against said connectors for resetting said movable switch contact to close said switch, the operation of said thermally responsive element positioning said movable contact for resetting by said means, said terminal connectors and switch being constructed and arranged relative to each other so that the position of said plug on said terminal connectors will not be disturbed by the switch opening movement of said movable contact by said thermally responsive element.

2. Safety switch and resetting mechanism for the electric circuit of a heated device comprising a thermostatic switch in said circuit, terminal connectors for said circuit adapted to be coupled with a plug of a current conductor, said switch comprising a plurality of contacts, at least one of which is movable, a thermostatically operated element for moving said contact to open said circuit, means for movably mounting said terminal connectors, said terminal connectors having a part movable therewith engageable with said movable contact and operable by pushing said plug against said connectors for resetting said movable switch contact to close said switch, the operation of said thermally responsive element positioning said movable contact for resetting by said movable part, said terminal connectors and switch being constructed and arranged relative to each other so that the position of said plug on said terminal connectors will not be disturbed by the switch opening movement of said movable contact by said thermally responsive element.

3. Safety switch and resetting mechanism for the electric circuit of a heated device comprising a thermostatic switch in said circuit, terminal connectors for said circuit adapted to be coupled with a plug of a current conductor, said switch comprising a plurality of contacts, at least one of which is movable, a thermostatically operated ele-

ment for moving said contact to open said circuit, spring means for movably mounting said terminal connectors, said terminal connectors having a part movable therewith engageable with said movable contact and operable by pushing said plug against said connectors for resetting said movable switch contact to close said switch, the operation of said thermally responsive element positioning said movable contact for resetting by said movable part, said terminal connectors and switch being constructed and arranged relative to each other so that the position of said plug on said terminal connectors will not be disturbed by the switch opening movement of said movable contact by said thermally responsive element.

4. Safety switch and resetting mechanism for the electric circuit of a heated device comprising a thermostatic switch in said circuit, terminal connectors for said circuit adapted to be removably coupled with a plug of a current conductor, said switch comprising a plurality of contacts, at least one of which is movable, a thermally responsive element operable by heat from said device for moving said contact to open said circuit, and means engageable with said movable contact and operable by pushing said plug against said connectors for resetting said movable switch contact to close said switch, the operation of said thermally responsive element positioning said movable contact for resetting by said means, said terminal connectors and switch being constructed and arranged relative to each other so that the position of said plug on said terminal connectors will not be disturbed by the switch opening movement of said movable contact by said thermally responsive element.

5. Safety switch and resetting mechanism for the electric circuit of a heated device comprising a thermostatic switch in said circuit, terminal connectors for said circuit adapted to be coupled with a plug of a current conductor, said switch comprising a plurality of contacts, at least one of which is movable, a thermally responsive element operable by heat from said device responsive to heat generated by operation of said device for moving said contact to open said circuit, means for movably mounting said terminal connectors, said terminal connectors having a part movable therewith cooperable with said movable contact for resetting the same to close said switch after said thermostatically operated element has cooled down, the operation of said thermally responsive element positioning said movable contact for resetting by said movable part, said terminal connectors and switch being constructed and arranged relative to each other so that the position of said plug on said terminal connectors will not be disturbed by the switch opening movement of said movable contact by said thermally responsive element.

6. Safety switch and resetting mechanism for the electric circuit of a heated device comprising a thermostatic switch in said circuit, said switch comprising a stationary contact, a movable contact operable for engaging said stationary contact to close said circuit, a bimetallic element responsive to heat generated by the operation of said device and comprising a lever, a second lever having a bifurcated end, one end of said first-mentioned lever having an edge upon which the bifurcated end of said second lever is rockably arranged, spring means connected to said levers for biasing said second lever into a position angularly related to said first-mentioned lever and on either side thereof, said movable contact

being carried at the other end of said second lever and operable when the bimetallic element is relatively cold for engaging said stationary contact to close said switch, said bimetallic element when subjected to heat resulting from the operation of said device being movable toward said stationary contact so as to cause said second lever to rock on the knife edge thereof sufficient to permit said spring means to move said second lever and contact carried thereby away from said stationary contact to open the switch, said circuit having terminal connectors to which a plug of a current conductor is adapted to be removably coupled, means for movably mounting said terminal connectors on said device, and means operable upon movement of said terminal connectors in one direction for cooperation with one of said levers to reposition the same after said bimetallic element has cooled down for positioning said movable contact to close said switch, the operation of said thermally responsive element positioning said movable contact for resetting by said means, said terminal connectors and switch being constructed and arranged relative to each other so that the position of said plug on said terminal connectors will not be disturbed by the switch opening movement of said movable contact by said thermally responsive element.

7. Safety switch and resetting mechanism for the electric circuit of a heated device comprising a thermostatic switch in said circuit, terminal connectors for said circuit, a plug of a current conductor removably coupled to said connectors, said switch comprising a plurality of contacts, at least one of which is movable, a thermally responsive element operable by heat from said device arranged for moving said contact to open said circuit without disturbing the relationship of said plug and connectors, said element and movable contact being constructed and arranged so that said element is not operable to reengage said contacts to close said circuit, and means engageable with said movable contact and operable by pushing said plug while coupled to said connectors for resetting said movable switch contact to close said switch, the operation of said thermally responsive element positioning said movable contact for resetting by said means.

8. Safety switch and resetting mechanism for the electric circuit of a heated device comprising a thermostatic switch in said circuit, terminal connectors for said circuit, a plug of a current conductor removably coupled to said connectors, said switch comprising a plurality of contacts, at least one of which is movable, a thermally responsive element operable by heat from said device arranged for moving said contact to open said circuit without disturbing the relationship of said plug and connectors, and means for movably mounting said terminal connectors, said terminal connectors having a part movable therewith engageable with said movable contact for resetting said movable switch contact to close said switch, the operation of said thermally responsive element positioning said movable contact for resetting by said part.

9. Safety switch and resetting mechanism for the electric circuit of a heated device comprising a thermostatic switch in said circuit, terminal connectors for said circuit, a plug of a current conductor removably coupled to said connectors, said switch comprising a plurality of contacts, at least one of which is movable, a thermally responsive element operable by heat from said device arranged for moving said contact to open

10 15 20 25 30 35 40 45 50 55 60 65 70 75

said circuit without disturbing the relationship of said plug and connectors, and spring means for movably mounting said terminal connectors, said terminal connectors having a part movable therewith engageable with said movable contact by pushing said plug against said connectors for resetting said movable switch contact to close said switch, the operation of said thermally responsive element positioning said movable contact for resetting by said means.

10. Safety switch and resetting mechanism for the electric circuit of a heated device comprising a thermostatic switch in said circuit, terminal connectors for said circuit, a plug of a current conductor adapted to be removably coupled to said connectors, said switch comprising a plurality of contacts, at least one of which is movable, a thermally responsive element operable by heat from said device for moving said contact to open said circuit, said element and movable contact being constructed and arranged so that said element is not operable to reengage said contacts to close said circuit as said element cools down, and means engageable with said movable contact and operable by pushing said plug while coupled to said connectors for resetting said movable switch contact to close said switch, said means being constructed and arranged so that said thermostatic element may open said switch without separating said plug from said terminal connectors, the operation of said thermally responsive element positioning said movable contact for resetting by said means.

11. Safety switch and resetting mechanism for the electric circuit of a heated device comprising a thermostatic switch in said circuit, said switch comprising a stationary contact, a movable contact operable for engaging said stationary contact to close said circuit, a bimetallic element responsive to heat generated by the operation of said device, a lever rockably arranged upon said bimetallic element, spring means connected to said lever for biasing said lever into a position angularly related to said bimetallic element and on either side thereof, said movable contact being carried by said lever and operable when the bimetallic element is relatively cold for engaging said stationary contact to close said switch, said bimetallic element when subjected to heat resulting from the operation of said device being movable toward said stationary contact so as to cause said lever to rock sufficient to permit said spring means to move said lever and contact carried thereby away from said stationary contact to open the switch, said circuit having terminal connectors to which a plug of a current conductor is adapted to be removably coupled, means for movably mounting said terminal connectors on said device, and means operable upon movement of said terminal connectors in one direction for cooperation with said lever to reposition the same after said bimetallic element has cooled down for positioning said movable contact to close said switch, the operation of said thermally responsive element positioning said movable contact for resetting by said means, said terminal connectors and switch being constructed and arranged relative to each other so that the position of said plug on said terminal connectors will not be disturbed by the switch opening movement of said movable contact by said thermally responsive element.
